UNITED STATES PATENT OFFICE.

CHRISTIAN AALBORG, OF PITTSBURGH, PENNSYLVANIA, ASSIGNOR TO WESTINGHOUSE ELECTRIC & MANUFACTURING COMPANY, A CORPORATION OF PENNSYLVANIA.

FAN.

Application filed September 10, 1924. Serial No. 736,818.

This invention relates to fans and more particularly to ceiling fans of the circulatory type.

The object of my invention, generally stated, is the provision of a circulatory fan that shall be simple and efficient in operation and readily and economically manufactured.

A more specific object of the invention is to provide for the rotation of a fan motor about an axis inclined to the axis of rotation of the fan wheel to give the fan wheel a circulatory movement, as it operates, in order to diffuse the current of air.

A further object of my invention is the provision of a motor housing which will permit movement of the motor shaft in different planes in order to give the fan wheel a circulatory motion.

It is also an object of the invention to provide for the delivery of electrical energy to a rotating fan motor.

Other objects of the invention will, in part, be obvious and, in part, appear hereinafter.

This invention, accordingly, is disclosed in the embodiment thereof shown in the accompanying drawing and comprises the features of construction, combination of elements and arrangements of parts which will be exemplified in the construction hereinafter set forth and the scope of the application of which will be indicated in the claims.

For a fuller understanding of the objects of the invention, reference may be had to the following detailed description, taken in connection with the accompanying drawing, in which

Figure 1 is a vertical sectional view showing, in detail, a device embodying my invention.

Fig. 2 is a horizontal sectional view along the line II--II of Fig. 1, showing details of construction, and

Fig. 3 is a sectional view along the line III--III of Fig. 1, showing features of the driving mechanism.

Referring now to the drawings, 10 designates generally a hanger provided for suspending the housing 15 from any overhead support. In order to facilitate the mounting of the housing, the hanger is made in

sections. As shown, the hanger includes a hook section 11 provided with a threaded portion adapted to engage in an overhead support and a tubular member 12 having a coupling 43 attached to its upper end.

In constructing the hook and coupling, they are so shaped that they may be connected and disconnected at will.

Since fans of this type are primarily designed for use in public places, such as offices and restaurants, it is desirable that they present an appearance in harmony with the other furnishings. Accordingly, a canopy 13 is positioned on the tubular member 12 to enclose the hook 11 and coupling 43. Further, the canopy 13 and the tubular member 12 constitute a conduit for the conductors 19, extending from the overhead support to the fan motor.

The housing, indicated generally at 15, includes two main sections 14 and 16. As shown, the section 14 is made in two parts, the upper part being substantially hemispherical in shape while the lower part is in the form of an inwardly curved rim.

In order to facilitate the mounting of the motor, shown generally at 17, in the housing, the rim 20 is removably attached to the upper section in any suitable manner, such as by the use of the screw bolts 21 shown in Fig. 1. As will be observed, the housing section 16 is also substantially hemispherical in shape and is suspended in the rim member 20, in a manner that will be set forth hereinafter.

The motor 17 may be of any well known type used in fan construction and is provided with a shaft 22 which extends beyond the motor casing to present an end for the reception of the fan wheel 23.

As shown, the motor is suspended in the housing section 15 and has the housing section 16 attached thereto. It will readily be understood that the housing section 16 may be attached to the motor casing in any suitable manner, such, for example, as by the use of the screws 24.

In order to give the fan wheel a circulatory movement, the motor 17 is rotatably suspended in the housing so that its shaft may be inclined to the axis of rotation. With a view to suspending the motor in the hous-

ing so that it may be rotated about an axis inclined to the axis of the shaft, a universal-joint connection is provided.

An examination of Fig. 1 will show that the universal-joint connection includes a plate 18 provided with two depending spaced arms supported in the housing section 15 by means of screws 25. Pivotaly mounted between the depending arms of the member 18 is a block 26 adapted to receive the bifurcated end of a stub shaft 27. It will be readily understood that, in order to permit the universal movement of the stub shaft, the arms of the bifurcated end of the stub shaft are pivotally connected to the block 26 so that the shaft may oscillate about an axis extending at right angles to the axis about which the block 26 may oscillate.

Since it is required that the motor 17 be suspended from the universal-joint connection in a manner to permit rotation, a block 28 is provided on the motor casing and has formed therein a bearing adapted to receive the stub shaft 27. It will be readily understood that the motor may be retained in position on the stub shaft in any one of a variety of ways and, in this particular construction, a connection is accomplished by forming a circumferential groove in the shaft to receive a set screw 29, mounted in the block 26.

The rotation of the motor on the stub shaft 27 is effected by means of a train of gears actuated upon the rotation of the motor shaft 22. It will be seen in Fig. 1, that a worm 30, having one end slotted, is loosely mounted in a bearing provided in the block 28 and is disposed in alignment with the shaft 22, the latter having a tongue formed on its end to project into the slot provided in the worm.

It will be apparent that the worm 30 may be retained in position in the bearing in any one of a variety of ways. In this particular embodiment of invention, in order to facilitate assemblage, the bearing is extended through the block 28 and is provided, at its outer end, with an internal thread for the reception of a cap 31, adapted to form a bearing for the end of the worm and to hold it in engagement with the shaft 22.

As illustrated in Fig. 3, a shaft 32 is rotatably mounted in a bearing provided in the block 28 and extends substantially at right angles to the axis of the worm 30. Connection is established between the shaft 32 and the worm 30 by means of a worm gear 33, fixed to the shaft 32 and disposed in a chamber formed in the block 28. The chamber in which the worm gear 33 is located is accessible from the end of the block and is closed by means of a cap 34. Formed on the opposite end of the shaft 32 is a pinion 35 disposed to mesh with a gear 36 keyed to the stub shaft 27.

In order to retain the axis of the shaft 22 inclined to the axis of rotation of the motor to give the fan wheel the desired circulatory movement, a brush-and-ring device is provided. As shown in Fig. 1, a ring 37 is disposed between a plurality of brushes 38, angularly spaced about the housing section 15. In this manner, the ring is retained centrally positioned in the housing section with its axis coincident with the axis about which it is desired to rotate the motor.

The ring 37 is carried by the housing section 16, which is attached to the motor, and it will be readily understood that the ring 37 may be set in any desired position relative to the motor. Accordingly, the shaft 22 may be retained inclined at any predetermined angle to the axis of rotation of the motor, depending on the path it is desired to describe by the fan wheel.

While the means provided to retain the shaft 22 inclined at the desired angle to the axis of rotation of the motor may be rigid, it is preferable that it should be resilient. Accordingly, the brushes 38 are slidably mounted in bushings 39 carried by the housing section 15 and urged toward the ring by means of springs 40.

It will be observed that these springs are held in position in the bushing and in engagement with the brushes by plugs 41. As shown, the plugs 41 are adapted to make threaded engagement with the bushings, thereby providing a structure that is easily disassembled for the replacement of parts. Further, the springs 40 urge the brushes forward to compensate for wear.

The motor 17 being rotatably mounted, the conductors 19 cannot be directly connected to a commutator or collector rings carried by the motor. Consequently, in order to supply the motor with electrical energy, collector rings 42 are disposed on the ring 37 carried by the motor and are located in alignment with the brushes 38.

Since it is necessary to insulate the rings 42 from one another and from the motor casing, the ring 37 is preferably made of some insulating material, such, for example, as hard rubber. The collector rings are constructed from some material capable of conducting electricity and are connected to the motor windings.

The brushes 38, which are disposed to engage with the collector rings 42, are made from carbon or any other suitable material having wear-resisting properties. Since these brushes are resiliently mounted, the danger of destruction due to the ring being thrown slightly off center during operation, is greatly reduced.

The conductors 19 may be connected to the brushes in any well known manner. In this particular structure, sleeves made of

some conducting material are placed on the brushes, and the conductors soldered or otherwise retained in engagement therewith.

In operation, when the motor circuit is closed, current flows through the conductors 19, the brushes 38 and collector ring 42 to the motor. When the motor is energized, the shaft 22 is rotated, and the pinion 35 is actuated through the worm 30, worm gear 33 and shaft 32. Since the pinion 35 is in mesh with the gear 36, the motor is revolved about the stub shaft 27. As the motor rotates, the ring and brush device function to retain the shaft of the motor inclined to the axis of rotation of the motor. The stub shaft, being suspended from the universal joint connection, is oscillated in different planes permitting the motor shaft to be oscillated in different planes.

Since the housing section 16, is symmetrically disposed about the axis of rotation of the motor, the lower portion of the shaft 22 describes a path lying within the ring 20. The housing section 16, the lower portion of which is hemispherical in shape, is rotated in the ring 20 about the axis of rotation of the motor, and the fan wheel 23 is given a circulatory movement.

Since the mechanism causing the rotation of the motor is connected to the shaft 22, the motor, by its own power, effects its rotation.

I would state, in conclusion, that, while the illustrated example constitutes a particular embodiment of my invention, I do not limit myself strictly to the details herein illustrated, since, manifestly, the same may be considerably varied without departing from the spirit of the invention as defined in the appended claims.

I claim as my invention:

1. In a fan, in combination, a motor disposed for rotation as a unit, a rotatable motor shaft extending at an angle to the axis about which the motor rotates, a fan wheel carried by the shaft, and means adapted to rotate the motor as a unit when the shaft is rotated thereby to give the fan wheel a circulatory motion as it operates.

2. In a fan, in combination, a housing, a motor provided with a rotatable shaft, said motor being rotatably disposed in the housing, a fan wheel carried by the shaft, and means carried by the housing co-operative to retain said shaft as it rotates inclined to the axis of rotation of the motor, and means for rotating the motor as the shaft rotates, thereby to give the fan wheel a circulatory movement as it rotates.

3. In a fan, in combination, a housing, a motor rotatably mounted in the housing, a motor armature shaft inclined to the axis of rotation of the motor, means carried by the housing to retain the motor armature

shaft inclined to the motor axis, and means actuated by the motor shaft to effect rotation of the motor.

4. In a fan, in combination, a housing, a motor provided with a rotatable shaft, said motor being rotatably disposed in the housing, a fan wheel carried by the shaft and resilient means disposed in the housing, co-operative to retain the shaft inclined to the axis of rotation of the motor, thereby to give the fan wheel a circulatory movement as the motor rotates.

5. In a fan, in combination, a motor provided with a shaft disposed for rotation about an axis extending at an angle to the shaft, a fan wheel carried by the shaft and means resiliently disposed in the housing, co-operative to retain the shaft inclined to the axis of rotation of the motor, said means being adapted to deliver electrical energy to the motor.

6. In a fan, in combination, a housing, a motor provided with a rotatable shaft mounted in the housing, said motor being disposed for rotation about an axis extending at an angle to the shaft, a fan wheel carried by the shaft, a ring-and-brush device co-operative to retain the shaft inclined to the axis of rotation of the motor.

7. In a fan, in combination, a housing, a motor provided with a rotatable shaft disposed in the housing, said motor being disposed for rotation about an axis extending at an angle to the shaft, a fan wheel carried by the shaft, a ring-and-brush device co-operative to retain the shaft inclined to the axis of rotation of the motor, said ring-and-brush device being resiliently disposed in the housing.

8. In a fan, in combination, a housing, a motor provided with a rotatable shaft mounted in the housing, said motor being disposed for rotation about an axis extending at an angle to the shaft, a fan wheel carried by the shaft, a ring carried by the motor, and a plurality of brushes disposed in the housing, co-operative with said ring to retain the shaft inclined to the axis of rotation of the motor.

9. In a fan, in combination, a housing, a motor provided with a shaft disposed in the housing to permit rotation about an axis extending at an angle to the shaft, a fan wheel carried by the shaft, a ring carried by the motor, a plurality of brushes disposed in the housing, co-operative with said ring to retain the shaft inclined to the axis of rotation of the motor, collector rings carried by said ring and arranged to make contact with the brushes to effect the delivery of electric energy to the motor.

10. In a fan, in combination, a housing, a motor provided with a shaft disposed in the housing to permit rotation about an axis extending at an angle to the shaft, a fan

wheel carried by the shaft, a ring carried by the motor, a plurality of brushes disposed in the housing, co-operative with said ring to retain the shaft inclined to the axis of rotation of the motor, a collector ring carried by said ring, and arranged to make contact with the brushes to effect the delivery of electrical energy to the motor, said ring serving to insulate the collector rings from one another and from the motor casing.

11. In a fan, in combination, a motor provided with a shaft, a fan wheel carried by the shaft, a universal-joint mounting adapted to support the motor, said mounting being disposed to permit rotation of the motor, and resilient means co-operative to retain the shaft inclined at an angle to the axis of rotation of the motor, thereby giving the fan wheel a circulatory movement.

12. In a fan, in combination, a motor provided with a rotatable shaft, a fan wheel carried by the shaft, a universal-joint mounting adapted to support the motor, said mounting being disposed to permit rotation of the motor, resilient means co-operative to retain the shaft inclined at an angle to the axis of rotation of the motor, and means actuated by the shaft to effect the rotation of the motor.

13. In a fan, in combination, a motor provided with a shaft, a sectional housing to enclose the motor, one section of the housing being fixed in position and another carried by the motor, a fan wheel carried by the shaft, said fan wheel being positioned outside of said housing, a universal-joint mounting disposed to support the motor in the fixed housing section, said mounting being disposed to permit rotation of the motor, and means co-operative to retain the shaft inclined to the axis of rotation of the motor.

14. In a fan, in combination, a motor provided with a shaft, a sectional housing for the motor, one section of the housing being fixed in position and another carried by the motor, a fan wheel carried by the shaft in position outside of said housing, a universal-joint mounting disposed to support the motor in the fixed housing section, said mounting being disposed to permit rotation of the motor and means co-operative to retain the shaft inclined to the axis of rotation of the motor, one of said housing sections being adapted to turn in the other, as the motor rotates, thereby to permit movement of the fan wheel in a circulatory path.

15. In a fan, in combination, a motor provided with a shaft, a fan wheel carried by the shaft, a sectional housing for the motor, one of said sections being fixed in position and the other movable, said fan wheel being positioned outside the housing, means to support the motor in the fixed housing, said means being adapted to permit rotation of

the motor and means co-operative to retain the shaft inclined to the axis of rotation of the motor, said movable housing section being carried by the motor and disposed to permit the rotation of the motor, thereby to give the fan wheel a circulatory movement.

16. In a fan, in combination, a motor provided with a shaft, a sectional housing for the motor, one section of said housing being fixed in position and the other being movable, a universal-joint mounting adapted to support the motor in the fixed housing section, said motor being rotatably connected to the universal-joint mounting, means co-operative to retain the shaft inclined at an angle to the axis of rotation of the motor, said movable housing section being carried by the motor and disposed to permit rotation of the motor, said shaft extending through the movable housing section, and a fan wheel mounted on the end of the shaft, the rotation of said motor thereby serving to give the fan wheel a circulatory movement.

17. In a fan, in combination, a motor provided with a shaft, a sectional housing for the motor, one section being fixed in position and the other being movable, a universal-joint mounting adapted to support the motor in the fixed housing section, said motor being rotatably connected to the universal-joint mounting, a plurality of co-operating contact members carried by the motor, a housing adapted to retain the shaft inclined to the axis of rotation of the motor, said contact members serving to transmit electrical energy to the motor as it rotates, and a fan wheel carried by the motor shaft.

18. In a fan, in combination, a motor provided with a shaft, a sectional housing for the motor, one section being fixed in position and the other being movable, a universal-joint mounting adapted to support the motor in the fixed housing section, said motor being rotatably connected to the universal-joint mounting, a plurality of co-operating contact members carried by the motor, a housing adapted to retain the shaft inclined to the axis of rotation of the motor, said contact members serving to transmit electrical energy to the motor as it rotates, a fan wheel carried by the motor shaft, and means actuated by the operation of the motor shaft to effect the rotation of the motor.

19. In a fan, in combination, a motor provided with a shaft, a sectional housing for the motor, one section being fixed in position and the other being movable, a universal-joint mounting adapted to support the motor in the fixed housing section, said motor being rotatably connected to the universal-joint mounting, a plurality of co-operating contact members carried by the motor, a housing adapted to retain the shaft inclined to the axis of rotation of the motor, said contact members serving to transmit electrical

energy to the motor as it rotates, said contact members carried by the housing being resiliently mounted, a fan wheel carried by the motor shaft and means actuated upon the operation of the motor shaft to effect the rotation of the motor, thereby serving to give the fan wheel circulatory movement.

20. In a fan, in combination, a motor provided with a shaft, a sectional housing for the motor, one section of the housing being fixed in position, a universal-joint mounting disposed in a fixed housing section, a stub shaft carried by said joint mounting, a motor rotatably mounted on said stub shaft, the motor shaft being inclined to the stub shaft, and means actuated upon the operation of the motor shaft to effect the rotation of the motor about said stub shaft.

21. In a fan, in combination, a motor provided with a rotatable shaft, said motor be-

ing disposed for rotation about an axis extending at an angle to the axis of the shaft, a fan wheel carried by the shaft, and means actuated by the motor shaft adapted to effect the rotation of the motor to give the fan 25 wheel a circulatory movement as it rotates.

22. In a fan, in combination, a support, a motor provided with a rotatable shaft and carried by the support, said motor being disposed for rotation about an axis extending at 30 an angle to the shaft, a fan wheel carried by the shaft, and means for rotating the motor as the shaft rotates, thereby to move the fan wheel in a predetermined path as it rotates.

In testimony whereof, I have hereunto subscribed my name this 4th day of September, 1924.

CHRISTIAN AALBORG.
